UNITED STATES PATENT OFFICE.

CHARLES L. STUBBS, OF AKRON, OHIO.

SHADE AND CURTAIN-POLE SUPPORT.

Application filed December 4, 1919. Serial No. 342,338.

To all whom it may concern:

Be it known that I, CHARLES L. STUBBS, a citizen of the United States, residing at Akron, in the county of Summit and State 5 of Ohio, have invented new and useful Improvements in Shade and Curtain-Pole Supports, of which the following is a specification.

This invention relates to improvements in 10 window fixtures and has particular relation to a combined curtain pole and window shade support.

The main object of the invention is to provide a strong, durable fixture which may be 15 used to support a window shade and curtain pole and which may be adjusted so that shades of varying widths may be used on the same window without removing the fixtures.

20 With the above and other objects in view, this invention consists in the novel construction, combination and arrangement of parts hereinafter described and illustrated in the accompanying drawing which forms a part 25 hereof, wherein I have shown a preferred embodiment of the invention, it being understood that changes, variations and modifications may be resorted to which come 30 within the scope of the matter hereinafter claimed.

In the drawings in which like numerals of reference are used to indicate corresponding parts in the several views,

35 Figure 1 is a front elevation of a shade mounted on a window by means of fixtures embodying this invention.

Figure 2 is a top view of one of said fixtures attached to a window casing and showing by dotted lines a portion of the shade 40 and curtain rod mounted thereon.

Figure 3 is a side elevation of the said fixtures mounted on a window casing as shown in Figure 2. Figure 4 is a similar side elevation of a fixture embodying this 45 invention showing adaptations of the invention and another method of attaching same to the casing.

Figure 5 is a perspective view of the shade-holding rod shown in Figure 1.

50 The invention contemplates two brackets each having a body 5, one of which is attached to each side of a window casing 6 so as to project therefrom at right angles to the face thereof. The body 5 is provided 55 with two laterally extending horizontal bores 7 and 8, the bore 8 extending there-

through adjacent the projecting end thereof, is adapted to receive a curtain rod 9 as shown by the dotted lines in Figure 2. Slidably mounted in the bore 7 is the rod 10 60 which is provided with a longitudinally extending row of closely spaced bores 11. The end of said rod having a slot 12 adapted to receive the axle of the ordinary shade. The body 5 is provided with a vertical bore 13 65 which extends from the upper surface of the body 5 to the bore 7. Mounted in the bore 13 is a pin 14, the upwardly extending end of which is engaged by a lever-like clip 17 which is fulcrumed on the body 5 at 15. 70 A spring 16 is positioned between the free end of said clip and the body 5 so as to normally force said pin 14 downwardly in the bore 13 and into one of the bores 11 in the rod 10. One end of the rod 10 is provided 75 with a slot 12 adapted to hold the squared supporting pin on one end of the shade roller and the other end of said rod is provided with a bore 18 adapted to rotatably hold the other end of the shade roller. The body 5 80 is rigidly attached to the plate 19 which is provided with apertures adapted to receive screws or other fastening means, whereby the bracket may be attached to the wood-work on the window. In the adaptation of 85 the invention shown in Figure 4, the body 5 is provided with apertures adapted to receive screws or other fastening means so that the fixtures may be mounted between 90 the window casing.

In use the brackets are rigidly secured to the trim of the window as shown in Figure 1. The free end of the clip 17 is pressed down and the rod 10 is inserted in the bore 7. The rods 10 are moved longitudinally in the bore 7 to accommodate the width of the shades to be used, the slot 12 being presented to one end of the shade and the bore 18 to the other end thereof and the shade is mounted therein in the usual manner, the pin 14 being forced downwardly in one of the bores 11. The pin 14 will hold the said rods against rotation and longitudinal movement. It will thus be seen that the rods 10 may be moved longitudinally in the bore 7 so that shades of varying widths may be used without changing the position of the fixture.

If desired the member 10 may be made oval or square or of any desired shape.

The fixture may also be used to hang maps and similar articles mounted on rollers.

Having thus described my invention what I claim as new and desire to secure by Letters-Patent is:—

1. In a window fixture, a bracket comprising in combination, a body, means to non-rotatably attach said body to a window casing, so the same will project at a right angle thereto, said body being provided with two horizontal bores which extend laterally therethrough, one of said bores located near the free end thereof and adapted to receive a curtain rod, a cylindrical supporting pin slidably mounted in the other bore; means mounted directly on said body to hold said pin in said bore, said means also adapted to prevent a rotary movement of said pin, the said pin provided at one end with means to operatively support a shade roller substantially as herein described.

2. A window fixture comprising in combination a body, means to rigidly secure said body to a window frame, a horizontal bore extending laterally through said body, a cylindrical member slidably mounted in said bore, said member being provided with a plurality of holes positioned therein in a longitudinally extending row, a vertical bore extending from the upper face of said body to the first mentioned bore, a pin mounted in said vertical bore, said pin

adapted to seat in any one of the plurality of holes in said member, means in the end of said member to operatively support a window shade roller, substantially as herein described.

3. In a window fixture, a pair of brackets, each comprising in combination a body, provided at its base with a plurality of bores adapted to receive screws for rigidly securing the body to a window casing, said body being provided with two horizontal bores which extend laterally therethrough, one of said bores located near the free end thereof and adapted to receive a curtain rod, a supporting pin, the other bore adapted to receive said pin which is adapted to be slidably mounted therein, said pin provided with a plurality of holes positioned therein in a longitudinally extending row, a vertical bore extending from the upper face of said body to the first mentioned bore, a pin slidably mounted in said vertical bore and adapted to seat in any one of the plurality of holes in said member, means in the end of said member to operatively support a window shade roller substantially as herein described.

In testimony whereof I have hereunto set my hand.

CHARLES L. STUBBS.
